UNITED STATES PATENT OFFICE

2,607,964

DOUBLE SASH METAL FRAME WINDOW

Hardwick B. Shook, Oklahoma City, Okla., assignor to Ventsulator Mfg. Co., Inc., Oklahoma City, Okla., a corporation of Oklahoma

Application March 11, 1948, Serial No. 14,367

1 Claim. (Cl. 20—55)

1. This invention relates to protective and sealing sash for windows of the double-hung type, and in particular a unique storm sash adapted to be positioned in a window frame between the outer parting strip and screen stop wherein with the usual full length window screen in the outer recess of the window frame the storm sash is substantially invisible and at the same time does not interfere with the normal operation of the sash.

The purpose of this invention is to provide storm sash that positively seals the window opening, preventing passage of air, dust, smoke and the like, and that remains permanently in position without interfering with normal operation of the sash or installation of the screen.

Various attempts have been made to combine storm sash with screens and the like but in the most successful installations either the sash or the screens or inserts in the sash or screens are removed during certain seasons of the year and in many cases refitting of the parts is required when they are reinstalled due to unexpected changes caused by atmosphere conditions or the like. With this thought in mind this invention contemplates a comparatively thin double grooved frame adapted to be positioned on the outer parting strip of the frame of a double hung window with a stationary glass corresponding with the upper sash of the window frame fixedly mounted in the upper part of the frame, and a movable glass corresponding with the lower sash of the frame slidably mounted in the lower part of the frame and positioned in an inner groove thereof wherein it is adapted to slide upward in front of the stationary glass.

The object of this invention is, therefore, to provide an improved storm sash that may be incorporated in the usual double hung window frame that permits normal operation of the window sash and screen and that may readily be opened for ventilating and other purposes.

Another object of the invention is to provide an improved storm sash that provides insulation and a positive seal preventing passage of air, dust, smoke and the like.

Another object of the invention is to provide improved storm sash that may be permanently mounted in a window frame between the outer parting strip and screen opening in which single or any number of panes of glass may be used.

Another object is to provide improved storm sash for windows and the like which eliminates noise.

A further object of the invention is to provide

improved storm sash that is permanently positioned in a window frame between the outer parting strip and screen opening which is of a simple and economical construction.

5 With these and other objects and advantages in view the invention consists of the new and novel combination, construction, and arrangement of parts as hereinafter more fully described, set forth in the claim appended hereto, and disclosed in the accompanying drawings forming part hereof, wherein:

Figure 1 is a view showing an outside elevation of a window with a screen positioned in the outer recess of the frame and with parts of the screen 15 broken away showing the improved storm sash behind the screen.

Figure 2 is a similar view with the screen removed illustrating the improved storm sash permanently mounted in the window frame.

20 Figure 3 is a vertical section through a window with the storm sash and screen mounted therein, taken on line 3—3 of Figure 1.

Figure 4 is a sectional plan through the window frame taken on line 4—4 of Figure 3 with parts 25 of the window and frame broken away.

Figure 5 is a vertical section similar to that shown in Figure 3 on an enlarged scale illustrating the shape and relative positions of the frame members of the storm sash.

30 Figure 6 is a sectional plan view taken on line 6—6 of Figure 5 with parts broken away.

Figure 7 is a detail illustrating a corner of the storm sash frame showing the upper stationary glass lowered slightly for the purpose of illustration, and with parts broken away.

35 Figure 8 is a similar view showing part of the lower part of a side of the storm sash frame with a section of the lower glass shown therein.

Figure 9 is a similar detail showing the upper 40 meeting rail of the storm sash with the rail of the lower glass dropped downward for the purpose of illustration, and with parts broken away.

Figure 10 is a similar view showing the lower meeting rail with parts broken away.

Figure 11 is a similar detail illustrating the sealing strip and handle at the lower edge of the lower glass with parts broken away.

Figure 12 is a detail showing a clip for holding the upper corners of the storm sash frame together.

Figure 13 is a plan view of an upper corner of the storm sash frame showing the clip mounted on the frame, and with part of the frame broken away.

Figure 14 shows a section through the corner

of the storm sash frame taken on line 14-14 of Figure 13 with parts broken away.

Figure 15 is a detail showing a section through a channel shape sealing strip for mounting the glass in the frame.

Figure 16 is an elevational view looking toward the intermediate part of the storm sash frame with parts broken way illustrating a brace for attaching the ends of the upper meeting rail to the sides of the frame.

Figure 17 is a sectional plan taken on line 17-17 of Figure 16 looking upward toward the under side of the upper meeting rail.

Referring now to the drawings wherein like reference characters denote corresponding parts the improved storm sash of this invention includes a frame having vertically disposed side bars 10 and 11, an upper horizontal bar 12, an upper stationary sash or glass 13, and a lower slideable sash or glass 14.

The storm sash frame is in the form of an inverted U open at the lower end and the sides and upper end are provided with a flange which is mitered at the upper corners as shown in Figure 2, providing flanges 15 and 16 on the bars 10 and 11, respectively, and 17 on the upper bar 12. The side bars 10 and 11 are formed with outer channels 18 and 19 and inner channels 20 and 21, respectively, and the upper bar 12 is also provided with a similar outer channel 22 and also a similar inner channel 23. The upper glass 13 is permanently mounted in the upper end of the outer channel and the glass is protected from the material of the bar by a U-shaped element having a relatively thick back 24 with tapering arms 25 and 26 wherein as the edge of the glass is forced into the channel the rubber or other resilient material retracts and binds the glass in the channel.

The lower edge of the upper glass 13 is forced into a channel 27 of a meeting rail 28 and the meeting rail is provided with an outer flange 29 that extends downward so that a flange 30 on the lower end thereof grips a strip 31 which has beads 32 and 33 on the edges, as shown in Figures 5 and 9, in which it will be noted that the bead 33 projects outward and engages the surface of a similar meeting rail 34 on the upper edge of the lower glass 14. The flange 30 has a lip 35 on the extending edge that fits in between the beads 32 and 33 so that the strip 31 is positively held in place.

The meeting rail 34 on the upper edge of the lower glass 14 is also formed with an outer flange 36 having a flange 37 at the upper end and the flange 37 has a lip 38 on the edge that grips a strip 39 between beads 40 and 41, and with the parts positioned as shown in Figure 5 the bead 40 projects outward and engages the surface of the meeting rail 28 and this bead coacting with the bead 33 provides a positive seal between the meeting rails joining the upper and lower glass members.

The lower edge of the lower glass 14 is secured in a channel 42 of a base bar 43 with a channel shaped element of rubber or the like, as shown in Figure 15, and the bar 43 is provided with an outer flange 44 with a depending lip 45 that grips a weather strip 46 which carries a tubular element 47, or a suitable yielding member, that is adapted to fit snugly over rough areas to compensate for uneven window sills and the like. The inner part of the base bar 43 is provided with an outwardly extending web or handle 48 by which the lower glass may be slid upward or downward.

The side edges of the lower glass 14 are provided with channel shaped members 49 having vertically disposed ribs 50 on the outer surfaces and with the ribs contacting the inner surfaces of the inner channels of the side bars 10 and 11 positive sealing will be obtained. These ribbed sealing members 49 are cemented or otherwise secured to the edges of the lower glass and slide upward and downward with the glass. The outer flange 51 of the inner channel of the frame is formed with a bulging section 52 which provides resiliency therein and also makes it possible to bend the flange outward or inward to decrease or increase the tension against the ribbed elements to facilitate sliding the glass and insure complete sealing.

The upper glass 13 is permanently mounted in the frame and although it is frictionally held in position it is desired to provide braces 53 and 54 under the ends of the meeting rail 28 on the lower edge of the upper glass, and these are provided with tongues 55 that extend into the outer channels of the side bars 10 and 11, as shown in Figure 17. The tongues are secured to the side bars by screws 56 and the braces are secured to the rail 28 by screws 57, as shown in Figure 16.

In order to prevent accidental separation of the side and upper bars of the frame, particularly in shipment the upper corners may be secured together by clips 58 having arms 59 and 60 with tongues 61 and 62 on the arms 59, and 63 and 64 on the arm 60, and in the assembled position the tongues are crimped into openings 65 and 66 in the frame.

The side and upper bars of the storm sash frame are positioned against the inner surface of the outer parting strip 67 of a window frame 68 and the flanges 15, 16 and 17 are secured to the outer surface of the strip by screws 69. With the elements in this position the upper sash 70 and the lower sash 71 of the window are free to slide upward and downward in the usual manner, and a screen 72 may be positioned in the outer recess or screen stop of the frame as indicated by the numeral 73, and the screen may be held by eyes 74 on hooks 75 or supported in any manner.

This complete storm sash may remain permanently in position and when it is desired to open the window for ventilation the lower glass 14 is raised and the ends of the base bar 43 provide guides preventing lateral movement of the lower glass in raising and lowering.

It will be understood that modifications may be made in the design or arrangement of the parts without departing from the spirit of the invention.

What is claimed is:

In a storm sash of the double hung window type having a frame provided with side rails with double channels in the inner edges thereof and an upper rail also having double channels in the inner edge connecting the upper ends of the side rails, the improvement comprising a transparent outer panel positioned with the sides and upper end thereof in the outer channel of the side rails and upper rail, a transparent inner panel positioned with the side thereof in the inner channel of the side rails of the frame, continuous sealing binding strips U-shaped in cross section extended around the edges of said outer and inner panels, a U-shaped sealing rail on the lower edge of the outer panel and having a downwardly extended flange on the outer surface with an inwardly extended strip on the lower edge 75 of the flange, a meeting rail carried by the lower

edge of the outer panel and secured thereto by the lip of the said depending flange, a U-shaped sealing rail on the upper edge of the inner panel with an upwardly extended flange having an outwardly extended lip on the upper edge carried by the inner side thereof, a resilient meeting rail on the upper end of the inner panel and secured thereto by the lip of the said upwardly extended flange thereof, a U-shaped rail on the lower edge of the inner panel having an outwardly extended handle on the inner side thereof and a depending flange with an inwardly extended lip on the lower edge on the outer side, and a tubular sealing strip with an upwardly extended web having an outwardly extended flange on the upper edge carried by the lip of the depending flange of the rail on the lower edge of the inner panel.
